[57] **CLAIM**

The ornamental design for a raised roof truck exterior surface, as shown and described.

DESCRIPTION

FIG. 1 is a perspective view of a raised roof truck exterior surface showing my new design;

FIG. 2 is a right side view of the raised roof truck exterior surface of FIG. 1;

FIG. 3 is a left side view of the raised roof truck exterior surface of FIG. 1;

FIG. 4 is a top view of the raised roof truck exterior surface of FIG. 1;

FIG. 5 is a bottom view of the raised roof truck exterior surface of FIG. 1;

FIG. 6 is a front view of the raised roof truck exterior surface of FIG. 1;

FIG. 7 is a back view of the raised roof truck exterior surface of FIG. 1;

FIG. 8 is a perspective view of a raised roof truck exterior surface showing a second embodiment of my new design;

FIG. 9 is a front view of the raised roof truck exterior surface of FIG. 8;

FIG. 10 is a right side view of the raised roof truck exterior surface of FIG. 8;

FIG. 11 is the left side view of the raised roof truck exterior surface of FIG. 8; and,

FIG. 12 is a top view of the raised roof truck exterior surface of FIG. 8, it being understood that the bottom and back views of the truck exterior surface of FIG. 8 are identical to those of the truck exterior surface of the embodiment of FIG. 1.

The broken lines shown in all views of the drawing are for illustrative purposes only and form no part of the claimed design.
